UNITED STATES PATENT OFFICE.

BENJAMIN ALEXANDER MATHEWS, OF SHREVEPORT, LOUISIANA.

LIFE-SAVING AND SALVAGING APPARATUS FOR USE WITH MARINE VESSELS.

Application filed October 24, 1927. Serial No. 228,319.

My present invention relates to improvements in life-saving and salvaging apparatus for use in marine vessels, and it is intended not only to provide means for locating the position of the sunken vessel after it rests on the bottom of the sea, and also means for facilitating the actual raising of the vessel after it has sunk, which means cooperate with the signalling and life-saving apparatus as will be hereinafter more fully described.

Reference is had to the accompanying drawings, in which like parts are indicated by similar reference symbols throughout the several views, and in which:

Figure 1 is a diagrammatic view showing a sunken ship with two sets of the apparatus mounted thereon, with the floats floating on the top of the water.

Figure 2 is a plan view of the part of the apparatus that is permanently attached to the ship, and which is used both in housing the float and in providing holding means which may be grappled from the surface of the water.

Figure 3 shows a section along the line 3—3 of Figure 2, and shows the float in dotted lines.

Figure 4 shows a central vertical section through the float, parts being shown in elevation.

Figure 5 shows a section along the line 5—5 of Figure 4 and looking down, parts being shown in elevation, and the wire cable being omitted from the reel.

Figure 6 is a detail view partly in section of one of the brackets and rollers used in suspending the cable drum, so as to permit the same to rotate about its transverse axis.

Figure 7 shows a section along the line 7—7 of Figure 6 and looking in the direction of the arrows.

Figure 8 is a detail showing, in side elevation, the cable drum as detached from the apparatus; and

Figure 9 is an enlarged sectional view showing the pivot on which the yoke carrying the cable drum is suspended.

Referring first to Figures 1 to 3, the vessel shown as submerged in Figure 1 is provided near the bow and stern with a skeleton frame

work A rigidly attached to the vessel in such a way that the grappling irons may be attached to it, and the vessel may be pulled up bodily from its position on the bed of the ocean, as will be hereinafter more fully described.

This skeleton frame work comprises a number of beams preferably in the form of T-irons A' which are radially disposed about a hollow central hub B secured to the deck C of the ship. The outer ends of these beams project downward as shown in Figure 3, and terminate in heavy bolts A², which preferably pass down to the keel as shown in Figure 1, or are otherwise secured to the structural parts of the ship so as to form a structure sufficiently strong to permit the ship to be pulled up bodily when the necessary lifting cables are attached to the structure.

The vertical portions of the beams A' are preferably attached to the flat ring D which is secured to the deck of the ship in any convenient way as by the bolts d. The radial portions of the beams A' are perforated to receive the heavy wire cables E which are spaced apart as shown in Figures 2 and 3, and permit the passage therethrough and the engagement therewith, of suitable grappling hooks or irons, not shown. The radial portions of these beams A' and the cables E provide a nest or housing for the float F which must be of quite a large size to secure the necessary displacement of water to permit the float to rise to the surface with the load of material carried thereby, which load will be hereinafter more fully explained.

Details of the float and parts carried thereby are shown in Figures 4 to 9.

Referring specially to Figures 4 and 5, the float is provided with a central hollow portion F⁰ exterior to which is the main air chamber F', and the outer chamber F². The walls of these air chambers are provided with braces G to render the same rigid against compressive strains. The top of the float is provided with a cylindrical chamber H closed by suitable cover H', which cover may be provided with hand holes h closed by suitable caps h'. The bottom of

this chamber H may be braced with a suitable ring H² in cross section in the form of an angle iron as shown in Figure 4. This chamber H provides a space for storage of medical and other supplies, concentrated food, inflatable belts or the like, which may be gotten at after the float rises to the surface as shown in Figure 1. Passing down through the supply chamber H is the housing I for the spindle J, which spindle may carry at its free end an electric light or a flare or other signalling devices K, which not being a part of my present invention will not be described herein. The lower end of the spindle J is provided with a head J' carrying the ball bearings L shown in detail in Figure 9, and above these ball bearings the yoke M is supported so as to rotate freely on the spindle J.

Between the top of the yoke M, another set of ball bearings L' may be provided if desired, the object being to permit the yoke M to rotate freely on the spindle J. Journalled in this yoke M is the cable drum N, on which the light wire cable O is wound. This drum is mounted in the approximate center of the air chamber F⁰, which is open at the bottom f⁰, as shown in Figures 4 and 5, to permit the free passage of the cable O as the float rises. The lower end of this cable is attached to the vessel in any convenient way as by means of the U-bolt O' shown in Figures 2 and 3. To prevent the cable from unwinding too fast, the ends of the drum N are provided with brake plates or wings n shown in Figures 4 and 8 which will engage the water when it enters the chamber F while the float is rising.

In order to allow the drum to rotate around its transverse axis and at the same time to steady the same as the float rises, I provide a track and bracket arrangement whereby the weight of the yoke and drum, and parts carried thereby, may be taken on a series of circular tracks on which run rollers. Such an arrangement is shown in Figures 4, 5, 6, and 7, where P' and P² represent brackets or arms attached to the yoke M and carrying near their ends rollers p. The brackets P' and P² may be provided with turnbuckles p' to adjust the attention of same if desired. These rollers travel on circular tracks Q, Q' and Q² supported by bracket P³, shown most clearly in Figure 4. Thus, if the float itself rotates as it rises to the surface, the downward strain on the cable O will tend to keep this taut and will permit the yoke to swivel freely about the spindle J.

On the exterior of the float body, I provide a number of hand grips R, which are arranged to be conveniently grasped by hand, so that persons in the water may hold on to same, or if desired these may serve as a ladder to permit any one to climb on top

of the float and gain access to the chamber H for the purpose of securing the supplies contained therein.

The operation of the devices is as follows:

The skeleton frame A being mounted and 70 securely attached to the body of the ship, and the float being nested in the same with cable O wound up on the drum N, and the end of said cable being attached to the U-bolt O', suppose the vessel to sink. 75

As the vessel sinks, the float will be automatically lifted off its seat, and the wire cable O will pay out until the float rises to the top.

While the float is still submerged or partly submerged, the water will flow into the bottom of the chamber f⁰, and compress the air in the central chamber F⁰, and the water will rise therein partly submerging the drum; and the wings N on the drum will churn the water, and serve as brakes to prevent the too rapid paying out of the cable. Any tendency for the float to swing around like a top would not affect the proper paying out of the cable, because the yoke carrying the cable drum will be held substantially steady while the float rotates about it. 80 85 90

Under certain conditions, persons may be saved by clinging to the hand grips R as the vessel sinks; but where the vessel sinks in deep water, such clinging would ordinarily be impossible; but at the same time when the vessel does reach bottom, the front will rest on the surface of the water, and these hand grips will serve as safety devices for persons floating in water nearby who can swim to the float and hold on to these grips or can even climb on top of the float, moreover, the supplies in the chamber H may be readily availed of by the persons in need of medical treatment or food, or life belts can be held in same. 95 100 105

Obviously the float may carry a flare or electric light, which will be put in operation when the float rises, or the float may carry a bell, not shown to indicate its position in the dark. 110

Such details can be obviously supplied, but they are no part of my invention, and will not be further described herein. 115

I have thus described the operation of the devices as a means for salvaging of the crew or passengers, and for locating the position of the sunken vessel. In order to use the arrangement for salvaging purposes, the cable will serve as a guide line to send down grappling hooks or other grappling devices carried by heavy cables, and these when lowered will be arrested somewhere within the skeleton frame from which the float has floated, and when these cables are pulled up, the grappled hooks will engage one or more of the stout cables E. A plurality of hooks and cables may be employed to engage each skeleton frame, and thus sever- 120 125 130

eral hoisting cables may be operated at once by salvaging vessels.

While I have shown in Figure 1 two of the sets of apparatus, one at the bow and the other at the stern of the vessel, it will be obvious that a single apparatus may be used; but three or more may be used if desired. It will also be obvious that the skeleton frame may be attached to the vessel in various ways, and that such an attachment would depend in a large measure on the structural design of the vessel itself, so that I do not mean to limit the invention to the precise construction of apparatus herein shown and described; nor do I mean to limit the invention to other details of construction, except as particularly pointed out in the claims.

Having thus described my invention, what I claim and desire to secure by Letters Patent of the United States is:—

1. Apparatus of the character described for use with marine vessels, comprising a skeleton frame securely attached to the vessel, and provided with a series of radially disposed, upwardly inclined beams forming a seat for the float, with cables connecting said beams, and adapted to be grappled by grappling hooks, with a float normally resting in said skeleton frame, but adapted to float upwards therefrom should the vessel sink, a cable drum journalled in said float, and a fine wire cable wound on said drum, and having one end secured to the vessel, and the other end secured to said drum.

2. Apparatus of the character described for use with marine vessels, comprising a skeleton frame securely attached to the vessel, and provided with a series of radially disposed, curved upwardly inclined beams forming a seat for the float, with cables connecting said beams, and adapted to be grappled by grappling hooks, with a pear shaped hollow float normally resting in said skeleton frame, but adapted to float upwards therefrom should the vessel sink, a cable drum journalled in the central air chamber of said float, and a fine wire cable wound on said drum, and having one end secured to the vessel, and the other end secured to said drum.

3. Apparatus of the character described for use with marine vessels, comprising a skeleton frame securely attached to the vessel, and provided with a series of radially disposed, curved upwardly inclined beams forming a seat for the float, with cables connecting said beams, and adapted to be grappled by grappling hooks, with a pear shaped hollow float normally resting in said skeleton frame, but adapted to float upwards therefrom should the vessel sink, a cable drum journalled in the central air chamber of said float, and a fine wire cable wound

on said drum and having one end secured to the vessel, and the other end secured to said drum, with means for braking said drum comprising wings projecting outwardly from the ends thereof, and adapted to engage any water rising in said central air chamber.

4. Apparatus of the character described for use with marine vessels, comprising a skeleton frame securely attached to the vessel, and provided with a series of radially disposed, upwardly inclined curved beams forming a seat for the float, with cables connecting said beams, and adapted to be grappled by grappling hooks, with a float normally resting in said skeleton frame, but adapted to float upwards therefrom should the vessel sink, said float being provided with a central air chamber open at the bottom, a cable drum journalled in the central air chamber of said float, and a fine wire cable wound on said drum, and having one end secured to the vessel, and the other end secured to said drum, with means for braking said drum to prevent too rapid paying out of said cable.

5. Apparatus of the character described for use with marine vessels, comprising a skeleton frame securely attached to the vessel, and provided with a series of radially disposed, upwardly inclined beams forming a seat for the float, with cables connecting said beams, and adapted to be grappled by grappling hooks, with a float normally resting in said skeleton frame, but adapted to float upwards therefrom should the vessel sink, said float being provided with a central air chamber open at the bottom, and with buoyancy chambers exterior to said central chamber, a cable drum journalled in the central air chamber of said float, and a fine wire cable wound on said drum, and having one end secured to the vessel, and the other end secured to said drum, with means for braking said drum comprising wings projecting outwardly from the ends thereof, and adapted to engage any water rising in said central air chamber.

6. Apparatus of the character described for use with marine vessels comprising a skeleton frame securely attached to the vessel, and provided with radial curved inclined beams forming a cup shaped seat for the float, a pear shaped hollow float normally resting in said seat, said float being provided with a central air chamber open at the bottom, and buoyancy chambers exterior to said central chamber, and with an upper supply chamber, a yoke swivelled in said central air chamber, a drum journalled in said yoke, and a wire cable wound on said drum and having its outer end secured to the vessel.

7. Apparatus of the character described

for use with marine vessels comprising a skeleton frame securely attached to the vessel, and provided with radial curved inclined beams forming a cup shaped seat for the float, a pear shaped hollow float normally resting in said seat, said float being provided with a central air chamber open at the bottom, and buoyancy chambers exterior to said central chamber, and with an upper supply chamber; a yoke swivelled in said central air chamber, a drum journalled in said yoke, and a wire cable wound on said drum and having its outer end secured to the vessel with means for braking said drum to prevent the too rapid paying out of said cable.

8. Apparatus of the character described for use with marine vessels, comprising a skeleton frame securely attached to the vessel, and provided with radial curved inclined beams forming a cup shaped seat for the float, a pear shaped hollow float normally resting in said seat, said float being provided with a central air chamber open at the bottom, and buoyancy chambers exterior to said central chamber, and with an upper supply chamber, a yoke swivelled in said central air chamber, circular tracks mounted in said central air chamber, brackets secured to said yoke, and having rollers travelling in said tracks, a drum journalled in said yoke, and a wire cable wound on said drum and having its outer end secured to the vessel.

9. Apparatus of the character described for use with marine vessels, comprising a skeleton frame securely attached to the vessel, and provided with radial curved inclined beams forming a cup shaped seat for the float, a pear shaped hollow float normally resting in said seat, said float being provided with a central air chamber open at the bottom, and buoyancy chambers exterior to said central chamber, and with an upper supply chamber, with hand grips secured on the exterior of the upper portion of said float, a drum journalled in said air chamber, and a wire cable wound on said drum and having its outer end secured to the vessel.

10. Apparatus of the character described for use with marine vessels, comprising a skeleton frame securely attached to the vessel, and provided with radial curved inclined beams forming a cup shaped seat for the float, a pear shaped hollow float normally resting in said seat, said float being provided with a central air chamber open at the bottom, and buoyancy chambers exterior to said central chamber, and with an upper supply chamber, hand grips secured on the exterior of the upper portion of said float, a yoke swivelled in said central air chamber, a drum journalled in said yoke, and a wire cable wound on said drum and having its outer end secured to the vessel.

11. In apparatus of the character described for use with marine vessels, a float normally carried by the vessel, but adapted to float upwards therefrom should the vessel sink, said float being provided with a central air chamber open at the bottom, and with buoyancy chambers exterior to said central chamber, a cable drum journalled in the central air chamber of said float, and a fine wire cable wound on said drum, and having one end secured to the vessel, and the other end secured to said drum. 65 70 75

12. In apparatus of the character described for use with marine vessels, a float normally carried by the vessel but adapted to float upwards therefrom should the vessel sink, said float being provided with a central air chamber open at the bottom, and with buoyancy chambers exterior to said central chamber, a cable drum journalled in the central air chamber of said float, and a fine wire cable wound on said drum, and having one end secured to the vessel, and the other end secured to said drum, with means for braking said drum comprising wings projecting outwardly from the ends thereof, and adapted to engage any water rising in said central air chamber. 80 85 90

13. In apparatus of the character described for use with marine vessels, a hollow float normally carried by the vessel, said float being provided with a central air chamber open at the bottom, and buoyancy chambers exterior to said central chamber, and with an upper supply chamber, a yoke swivelled in said central air chamber, a drum journalled in said yoke, and a wire cable wound on said drum and having its outer end secured to the vessel with means for braking said drum to prevent the too rapid paying out of said cable. 95 100 105

14. In apparatus of the character described for use with marine vessels, a hollow float normally carried by the vessel, said float being provided with a central air chamber open at the bottom, and buoyancy chambers exterior to said central chamber, and with an upper supply chamber, a yoke swivelled in said central air chamber, circular tracks mounted in said central air chamber, brackets secured to said yoke, and having rollers travelling in said tracks, a drum journalled in said yoke, and a wire cable wound on said drum and having its outer end secured to the vessel. 110 115

15. In apparatus of the character described for use with marine vessels, a hollow float normally carried by the vessel, said float being provided with a central air chamber open at the bottom, and buoyancy chambers exterior to said central chamber, and with an upper supply chamber, with hand grips secured on the exterior of the upper portion of said float, a drum journalled in

said air chamber, and a wire cable wound on said drum and having its outer end secured to the vessel.

16. In apparatus of the character described for use with marine vessels, a hollow float normally carried by the vessel, said float being provided with a central air chamber open at the bottom, and buoyancy cham-

bers exterior to said central chamber, and with an upper supply chamber, hand grips secured on the exterior of the upper portion of said float, a yoke swivelled in said central air chamber, a drum journalled in said yoke, and a wire cable wound on said drum and having its outer end secured to the vessel. 10

BEN ALEXANDER MATHEWS.
